(57) **CLAIM**

The ornamental design of a combined conveyor roller and tapered sleeve, as shown and described.

DESCRIPTION

FIG. 1 is a perspective view of a combined conveyor roller and tapered sleeve showing our new design;

FIG. 2 is a side view thereof;

FIG. 3 is an end view thereof; and,

FIG. 4 is an opposite end view thereof.

The roller is shown broken away in FIGS. 1 and 2 for convenience of illustration.
